UNITED STATES PATENT OFFICE

EMIL H. PIRON, OF DETROIT, MICHIGAN, ASSIGNOR TO NOBLE AND HARRIS, OF DETROIT, MICHIGAN

TRAFFIC SIGNAL

Application filed January 31, 1929. Serial No. 336,401.

This invention relates to traffic signals and has for its object to provide an improved means for indicating traffic directions which will be clearly visible during periods of day-light and darkness.

Another object of the invention is to provide a traffic signal which readily lends itself to timing or to re-timing to meet changing conditions and which, when synchronized 10 with other signals in series, will constantly operate in any desired sequence without departure from predetermined time intervals of signal indication.

A further object is to provide a traffic signal which may perform the additional duties of a street light and illuminated street marker without requiring additional lighting current over and above that ordinarily employed to operate the signal itself.

20 A more specific object of the invention is to provide a traffic signal wherein reflecting surfaces are employed to project clear-cut images of lettering or colored light rays both by artificial and natural light in the direction 25 of each lane of traffic for control thereof and to provide means for periodically varying the reflected images in a predetermined orderly sequence.

In carrying the invention into effect, I employ preferably one reflecting surface for each lane of traffic to be controlled. The colored signals or directions reflected may be secured by transparent or translucent screens so arranged as to permit rays of light to filter 35 therethrough onto the reflecting surfaces. If desired, of course, illuminated figures, letters or colored surfaces might be employed for reflection, but I recommend the use of rays filtering directly through some colored translucent or semi-transparent material such as 40 glass. In the preferred embodiment, the light filter is of the form of a segmental glass disc rotatably mounted in a favorable position with respect to the reflecting surfaces, each 45 segment thereof being of a size and color to be hereinafter more fully explained. The colored discs are so housed as to be capable of utilizing the natural daylight rays during the daytime, whereas a lamp in the roof of 50 my device is illuminated at night to provide

a source of light for reflections during periods of darkness.

Among the other objects of my invention, I may also relate insured constancy of operation, improved appearance, improved utility 55 due to its utility as a street indicator and street light in addition to its duties as a director of traffic, cheapness of manufacture, ease of installation and decreased cost of operation and maintenance due to its half time use 60 of artificial lighting and to its simplicity of construction.

Other objects and advantages will become apparent as reference is made to the accompanying drawings wherein is illustrated, by 65 way of example, one embodiment of my invention and wherein:

Figure 1 is a front or side elevation of my improved traffic signal;

Figure 2 is a transverse sectional view taken 70 through the center of Figure 1;

Figure 3 is a horizontal sectional view taken along line 3^x—3^x of Figure 2; and

Figure 4 is a horizontal sectional view taken along line 4^x—4^x of Figure 2.

Referring more particularly to the drawings, reference character 1 refers to a support of any desired type to which is attached the traffic signal designated generally by the numeral 2, it being obvious that the signal may be suspensable or otherwise mountable if desired. In the illustration shown, the signal 2 has a flared base 3 upon which is mounted a two part housing 4, 5, the latter having sidewalls preferably made of a transparent or translucent material, such as glass, which converge upwardly to a reflector 6 for a lamp 7. Stays or braces 8 provide ample support for a reflecting cap 6 which may extend well down along the sidewalls of the housing, or, 85 preferably, limited in extent to a horizontal plane immediately above or directly through the center of the lamp 7 so that the rays of the lamp may be utilized to illuminate the vicinity around the signal in the manner of a street 90 light.

The lower part 4 of the housing serves as protection, and, if desired, as lenses for a plurality of angularly disposed reflecting surfaces 9, herein shown as being four in number. 100

These reflectors are so placed as to directly receive the rays of light from the lamp 7 and also natural daylight rays entering in the daytime through the light permeable side-walls of the upper housing 5 whereby such rays are reflected in the direction of the various lanes of traffic, herein regarded as being four.

Immediately above the reflecting surfaces 9, a segmental light-permeable disc 10 is rotatably mounted for interception of the rays of light traveling toward the said surfaces. The disc is, in this instance, as illustrated in Figure 4, composed of four segments, two of which 10 and 11 are three times as large as the other two 12 and 13. The segments 10 and 11 are of colored glass and may be of the color most generally used to denote "Stop," namely, red. The segments 12 and 13 may be of the conventional color for "Go," namely, green. By this arrangement, with the disc in the position shown, it is obvious that traffic may proceed along one street while being held from crossing transversely thereof. Upon rotation of the disc through one-eighth of a circle or forty-five degrees the green segments will each be between two reflecting surfaces as indicated by the dotted positions 14 and directly over two of four shields 14' spaced at these two positions. There are two other shields 14'' at points ninety degrees removed from this position. The green segments will therefore be entirely shielded and red rays will be reflected from all surfaces, holding up traffic in all directions. Further rotation of the disc through forty-five degrees exposes the green segments to the reflectors in the dotted position indicated as 15.

It is preferable that the disc should rotate very quickly during changes of position and that it should, of course, stop for a desired number of seconds in each position. It is also desirable that the timing be such as to lend itself to ready changes for purposes of synchronization with other signals. For this purpose, I have illustrated one way in which this may readily be affected although I desire to state that the timing may readily be affected from a remotely located board as in the manner controlling lights in many traffic signals now known, and that this particular means for effecting operation is to be considered merely illustrative of one mode of carrying out operation.

A small electric or other motor 16, of any suitable type is suitably mounted above the segmental disc. Mounted on the motor shaft is a gear 17 which meshes with a gear 18 through which extends the shaft 19. Mounted on this shaft is a drive wheel 20 for actuation of a variable speed sprocket wheel 21 mounted on a shaft 22. Drive wheel 20 is equipped with two driving pins 23 and 24, one of which is located at a greater distance from the center of the wheel than the other

for a purpose to become hereinafter apparent, it being noted at this point that the inner pin 23 is so placed as to provide a driving connection for the sprocket 21 when contacting the outer teeth 25 thereof while the pin 24 is so placed as to engage the inner teeth 26 when in proper rotative position. The segment carrying the teeth 26 is depressed as clearly shown in Figure 2 so that the pin 24 passes underneath the segment carrying teeth 25 without interference.

Mounted on the shaft 22 is a second drive wheel 27 equipped with two pins 28 both of which are equally spaced from the center of the wheel in position to drive a second sprocket wheel 29 mounted on a shaft 30 to which is rigidly attached the segmental color disc 10, 11, 12 and 13.

The operation is as follows: Suppose the motor shaft has a constant speed of one revolution per second, then the speed of the gear 18 and shaft 19 should be about one revolution every two and a half seconds. This, of course, means that the drive wheel 20 revolves once in every two and a half seconds and that at such intervals either the drive pins 23 or 24 will actuate the sprocket wheel 21 a distance which will be equal to the width of the teeth. If the wheel 20 is turning in the direction indicated in Figure 3 the pin 24 after approximately two-thirds of a revolution will engage a lower tooth 26 imparting one-eighth of a revolution to the sprocket wheel 21 which in turn rotates the second drive wheel 27 (Figure 4) through one-eighth of a revolution from the position shown whereby the sprocket wheel 29 and the signal disc are substantially instantaneously rotated through one eighth of a revolution. Thus, if we assume the segments to have been as indicated in Figure 4, the green segments 12 and 13 would be instantaneously removed to a shielded position between the reflecting surfaces. The disc will stop at this point for two and a half seconds or until the pin 24 makes another complete revolution, whereupon the lower tooth 26 is engaged for actuation of one-eighth of a revolution whereupon the green segments are instantaneously moved to the dotted positions indicated by numerals 15. The period of revolution of the driveshaft 19 and the distance of the pin 24 from the shaft then determine the length of time to be allowed between reversal of signals.

After the green light has been changed to its new position, the inner pin 23 upon the next revolution of the drive wheel 20 engages an outer tooth 25, one tooth being driven forward the length of its width every two and a half seconds during which time the drive wheel 27 is merely revolving its pins 28 freely until a revolution again places them in position for further actuation of the colored disc. Thus if we employ the number of

teeth shown, twenty-five in number, it will take $67\frac{1}{2}$ seconds before the signal again changes to red on all sides. With this arrangement, equal time is given to all traffic lanes, however, if desired to allow one line of traffic more time than another it is necessary to provide two depressed segments such as 26 and to proportion the number of teeth 25 which represent disc rest periods to meet the need.

The variable sprocket wheels 21 need not be finely machined and can be cheaply manufactured by stamping. As this is the only element to be replaced in case of a change in timing it is rather a simple matter to carry a few extra sprocket wheels in stock for this purpose.

In order to synchronize the signal with other signals, in view of the unvarying speed of the driving unit or motor 16, it is merely necessary to turn all lights to a full red position and then allow each one to advance a certain number of predetermined seconds in turn while the first signal is cut off which will represent a definite number of sprocket teeth advancement. This timing, when once set, will never vary with the motor recommended, so that the lights will not get out of synchronization provided they are thereafter turned on and off in unison.

A housing 30 for the disc controlling mechanism may assume the shape of a quadrilateral pyramid, if desired, it being necessary to so construct the housing that it does not interfere with the rays from the lamp 7. The sides of this housing, being surrounded by glass, may readily be utilized as a street marker in the manner shown in Figure 1. The advantage of this arrangement is that it is well lighted at night and furthermore it is a convenience to the motorist which likewise permits him to give his attention to driving whereas a diversion of his attention for the purpose of seeking information as to his whereabouts might lead to an accident.

Insofar as this invention is concerned, it will be readily appreciated that illuminated figures, devices or surfaces may be considered as the equivalent of a transparent screen, although I prefer the latter, as such illuminated surfaces may be viewed by reflection through the reflecting mirrors quite effectively and traffic accordingly directed. It will also be apparent that the invention is not limited to a single disc or screen and that the several reflectors may be equipped with separate individual operated screens, for instance; and many arrangements may be used to embody the invention and that numerous types of drives might be employed to vary the signals thereof and I therefore desire to be limited in the construction and application of my invention only by the scope of the appended claims, wherein:

What I claim is:

1. In a traffic signal, a reflecting surface, a plurality of signals to be reflected, and means for periodically changing the signals so reflected.

2. In a traffic signal, a reflecting surface, a plurality of signals to be reflected, and means for periodically shifting said signals to reflective and non-reflective positions with respect to said surface.

3. In a traffic signal, a plurality of reflecting surfaces, a plurality of signals to be reflected by said surfaces, and means for periodically exposing said signals to said surfaces for reflection thereby.

4. In a traffic signal, a plurality of angularly disposed reflecting surfaces, one of said surfaces facing each direction of traffic, light transmitting signals above said reflecting surfaces and means for periodically rotating said signals to reflective and non-reflective positions with respect to said surfaces.

5. In a traffic signal, a plurality of angularly disposed reflecting surfaces, a disc having segmental light transmitted signals above said surfaces for reflection thereby and means for periodically rotating said disc whereby the reflections of said signals will periodically change.

6. In a traffic signal, a plurality of angularly disposed reflecting surfaces, a translucent disc comprised of colored segments rotatably mounted above said surfaces for reflection thereby, said discs allowing daylight rays to pass therethrough whereby the colors of said segments are reflected from said reflecting surfaces and means for rotating said disc whereby the colors reflected will periodically change.

7. In a traffic signal, a plurality of instructive signals, reflecting surfaces for said signals, timed means periodically exposing said signals to said surfaces in rotation, and an artificial light for illuminating said reflecting surfaces.

8. In a traffic signal, a plurality of instructive signals, reflecting surfaces for said signals, timed means periodically exposing said signals to said surfaces in rotation, said reflecting surfaces being adapted for illumination by daylight during the daytime and by artificial light during periods of darkness.

9. In a traffic signal, a disc comprising segmental translucent colored segments, reflecting surfaces for rays of light passing through said segments, timed means for intermittently rotating said disc whereby the color of the reflected rays may be varied, and a lamp above said disc for illuminating said reflecting surfaces through said segments.

10. In a traffic signal, a plurality of transparent or translucent signals, angularly disposed reflecting surfaces for said signals, timed means for periodically exposing said signals singly to said surfaces, said signals being arranged to pass rays of daylight for

reflection during the daytime and rays from a lamp during periods of darkness.

11. In a traffic signal, a housing, a lamp having a reflector therefor in the top of said housing, a truncated pyramid having reflective sides within said housing below said lamp, said sides each being directly exposed to the rays of said lamp, translucent colored signals between said lamp and said surfaces and means for periodically rotating said signals whereby the colors reflected by said surfaces will periodically change.

12. In a traffic signal, a housing having transparent or translucent walls, a lamp having a reflector in the top of said housing, a truncated pyramid having reflective sides within said housing below said lamp, each of said sides being directly exposed to the rays of said lamp, translucent colored signals for intercepting rays of sunlight through the transparent walls of said housing and the rays of light from said lamp and means for periodically changing the color of said signals for reflection by each of said surfaces.

13. In a traffic signal, a reflecting surface, a plurality of signals for reflection by said surface and means for instantaneously shifting said signals from reflective to non-reflective positions between periods of rest.

14. In a traffic signal, a plurality of reflecting surfaces, a plurality of signals for reflection from said surfaces, and means for presenting each of said signals to each of said surfaces singly and in rotation for reflection thereby, said means instantaneously varying the signals presented during periods of rest.

15. In a traffic signal, a plurality of reflecting surfaces, a rotatable signal disc comprising colored segments, each segment of said disc presenting a directing color for reflection by each of said surfaces, a constant speed motor, and driving means between said disc and said motor, said means instantaneously rotating said disc over one segment between periods of rest whereby the directions to traffic may be quickly varied according to the nature of the signal reflected.

16. In a traffic signal, four angularly disposed equally spaced reflecting surfaces, a translucent disc comprising eight segments of equal size, six of said segments being red, two of said segments being green, four shields, each having the dimensions of one of said segments equally spaced below said disc, whereby four of said segments may be shielded from said reflecting surfaces, means for periodically rotating said disc, said disc upon rotation causing a reflection of red rays from two opposite reflecting surfaces and green rays from the other two reflecting surfaces in one position, red rays from all four surfaces at another position and green and red rays under actuation to a further position.

In testimony whereof I affix my signature.
65 EMIL H. PIIRON.
